CARTRIDGE BOX FILLING DEVICE

Charles E. Wallick, Denver, Colo.

Application March 10, 1942, Serial No. 434,079

10 Claims. (CL. 86—47)

This invention relates to a machine for filling partitioned cartons with individual items and more particularly to a machine for filling cartridge boxes.

The principal object of the invention is to provide a machine which will eliminate all hand labor and which will fill cartridge boxes at an extremely high rate of speed.

Other objects of the invention are to provide a machine of this character in which empty boxes will instantly replace filled ones so that the machine will be continuous in its operation; to provide means for causing all of the cartridges to fall into the boxes with their bullet extremities downward; and to provide a machine in which there will be no possibility of accidental discharge of the cartridges.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a side view of the improved cartridge box filling machine;

Fig. 2 is a detail plan view of the feed belt; Fig. 3 illustrates the type of box the machine, as illustrated, is designed to fill;

Fig. 4 is a slightly enlarged cross section through the machine, taken on the line 4—4, Fig. 1;

Fig. 5 is an enlarged detail view of the type of receiving slot employed in the table top of the machine;

Figs. 6 and 7 are cross sections through the slot of Fig. 5, taken on the lines 6—6, and 7—7, respectively;

Fig. 8 is a plan view of the slotted portion of the table top, taken on the line 8—8, Fig. 9;

Fig. 9 is a section through the feeder portion, taken on the line 9—9, Fig. 8;

Figs. 10, 11, and 12 are diagrammatic plan views of the box shelf of the improved machine illustrating successive steps in the box feeding operations;

Fig. 13 is a detail plan view of the box removing shuttle; and

Fig. 14 is a detail section through the feeder for the incoming boxes, taken on the line 14—14, Fig. 10.

The machine may be arranged to fill a box of any type having any desired number of compartments. It is more particularly intended for use with standard cartridge boxes such as illustrated at 11 in Fig. 2. The usual cartridge box is provided with a hinged lid 12 and is divided by a central partition 13 into two longitudinally extending halves. The central partition 13 carries separating flaps 14 which divide each half into ten compartments, each of which supports a single cartridge 15 vertically. Thus, the standard boxes are designed to receive twenty cartridges and the present machine will be described as applied to such a box although it is, of course, not limited to this particular type of box.

The improved machine comprises a supporting frame 16 carrying a table top 17 upon which a slotted slide 18 reciprocates longitudinally. A chamber block 19 is fixedly supported above the slotted slide 18. The table top is formed with two longitudinal series of laterally extending slots 20, there being ten parallel slots in each series of a size to pass a horizontally positioned cartridge. The two series of slots correspond to 25 the compartments in the two halves of the box 11.

Each of the slots 20 carries, at each of its extremities, two inwardly extending projections 21 spaced apart sufficiently far to allow the bullet extremity of the cartridge to pass therethrough 30 but not sufficiently far to allow the cap flange of the cartridge to pass, as illustrated in Fig. 5. Thus whenever a cartridge falls into one of the slots 20, the cap extremity thereof will be supported for an instant until the bullet extremity swings downwardly so that all cartridges will fall with their bullets downward regardless of their positions in the slots 20.

The slots in the slide 18 correspond in position and number to the table top slots 20. The cartridges are fed into the slots of the slide from the chamber block 19. The latter is provided with slotted chambers 49 which register with the slots of the slide when the slide is at one extremity of its stroke. The slots in the slide register 45 with the slots 20 when the slide is at the other extremity of its stroke. The slide 18 has a thickness of one cartridge, the chamber block has a thickness of two or more cartridges.

The cartridges are fed into the chambers 49 of the chamber block by means of an endless, slotted feed belt 25 having two rows of cartridge receiving pockets 26 which align with the slots in the chamber block. The belt 25 slides over the chamber block and passes round two belt wheels 55 27, there being one belt wheel at each extremity

of the machine. The cartridges are fed into the belt pockets 26 from a feed hopper 24 positioned against one of the belt wheels 27. Bottom plates 28 are placed beneath the belt 25 to prevent the cartridges from falling from the open pockets therein. The belt is driven from an electric motor 29. The motor 29 drives a countershaft 30 through the medium of a suitable transmission belt and the wheels 27 are driven from the countershaft 30 through the medium of a similar belt.

The slotted slide 18 is reciprocated by means of a rocking lever 31 which is journaled in suitable bearings 32 below the table top. The upper extremity of the rocking lever is connected to a suitable ear 33 on the slide 18. The rocking lever is reciprocated back and forth through the medium of a connecting rod 34 extending from between a pair of crank discs 35 on the countershaft 30. The relation of the crank and the rocking lever is such that the slide 18 will reciprocate an amount equal to the width of the individual slots 20 at each revolution of the countershaft 30.

A hopper 22 is positioned below the slotted portion of the table top. This hopper is divided by means of inclined internal partitions 23 into twenty compartments, each compartment terminating over one of the cartridge compartments of a box 12. The hopper serves to guide the cartridges falling through the slots 20 into the chambers of the cartridge box.

The empty cartridge boxes are delivered to the machine through a feed channel 36 and the filled boxes move away from the machine through a delivery channel 37. Both channels are supported on suitable shelf 38 in the frame 16. The boxes may be moved along the channels in any desired manner such as by means of standard conveyor belts, such as indicated in broken line at 39 in Figs. 10 to 12. The two channels 36 and 37 are separated a distance slightly in excess of the thickness of one box. A box pusher 40 serves to push the boxes from the feed channel 36 to the delivery channel 37. As the boxes move to the position to be filled, their lids 12 engage a stationary lid lifting hook 48 which swings the lid upwardly and outwardly to the open position.

The boxes are removed when filled by means of a reciprocating shuttle 41. The shuttle is positioned in the bottom of the delivery channel 37 and supports the entire weight of the boxes at their filling position. The pusher 40 is urged against the boxes by means of suitable compression springs 42 and is forced from the boxes against the action of the springs by means of a hinged cam follower 43. The cam follower is hinged on the bottom of the pusher and its extremity rides against a cam surface 44 formed on one side of the bottom of the shuttle 41.

The shuttle is held in place beneath the bottom of the channel 37 by means of suitable slides 45 and it is reciprocated through the medium of a wrist pin 46 with which the extremity of the connecting rod 34 connects. The rocking lever 31 contains a slot 47 for receiving the pin 46 so that the lever will be moved in synchronism with the movements of the shuttle 41.

Operation

The feed hopper 24 is maintained filled with cartridges in any desired manner such as by means of suitable belt conveyor (not shown). The belt 25 travels away from the hopper on the upper side of the machine and as the belt passes through the pile of cartridges the slots 26 therein fill

with cartridges. The cartridges are carried across the top of the machine and over the chamber block 19. Should any of the chambers in the block 19 be empty or partially empty, cartridges will drop from the belt into them. Should all of the chambers be filled, the cartridges will be simply carried around with the belt until a chamber is ready to receive them.

At each revolution of the countershaft 30 the slide 18 will move its slots under the chambers in the block 19 allowing the lowermost cartridges to fall therefrom into the slots of the slide. The slide will then reciprocate to position its slots over the slots 20 and all of the cartridges in the slide will simultaneously drop, with their bullet extremities downward into the hopper 22 which will align them with their proper compartments in the box positioned to receive them.

As the slide 18 returns to be refilled, the shuttle 41 moves to the left and carries the filled box from its position below the hopper. As the shuttle 41 starts to the left, as shown in Fig. 11, the cam surface 44 acts against the follower 43 to force the pusher 40 away from the second succeeding box, as shown in Fig. 11, to relieve the pressure on the filled box so that the shuttle may remove it. The pusher continues back sufficiently far to allow a third box to enter in front of it from the feed channel as shown in Fig. 12. When the filled box has moved to the position of Fig. 12, the follower 43 will snap over the right extremity of the shuttle 41 allowing the springs 42 to snap the second and third boxes to the position of Fig. 10, thus placing the second empty box in position for the next fall of cartridges. As each box moves to the filling position its lid will be lifted and opened by the lid lifting hook 48.

While the machine has been illustrated and described as used for filling boxes with cartridges and while the claims refer to a cartridge box filling machine, it is desired to be understood that the cartridges are simply examples of any desired articles which it is desired to be placed into partitioned boxes.

Having thus described the invention what is claimed and desired secured by Letters Patent is:

1. A cartridge box filling machine comprising: a multiple compartment hopper having a reduced lower extremity corresponding to the shape, arrangement, and position of the box to be filled; a top over said hopper provided with cartridge receiving slots, there being one slot for each hopper compartment; a slide member moving over said top and having slots corresponding to the receiving slots in said top; a chamber member above said slide member; cartridge receiving chambers in said member registering with the slots in the slide member at one extremity of the latter's movement; a traveling member moving over said chamber member; cartridge receiving pockets in said traveling member corresponding in position and spacing to the chambers in the chamber member; and a feed receptacle positioned against said traveling member so that the latter forms a wall of said receptacle so that a pile of cartridges will be held against said traveling member from which individual cartridges are caught by the pockets in the traveling member.

2. Means for feeding a plurality of elongated articles into vertical aligned position in a receiving box comprising: a hopper terminating above said box; a plurality of vertically extending guide compartments in said hopper, the upper

extremities of said compartments being elongated to receive said articles horizontally, the lower extremities thereof being reduced to discharge said articles vertically into said box; a horizontal top plate covering said hopper and provided with laterally extending elongated slots for receiving individual articles horizontally, each slot aligning with one of said compartments; a slide plate having similarly slots positioned to register with the first elongated slots when said slide plate is moved in one direction and to misalign therewith when moved in the other direction, said slide plate having a thickness sufficient only to allow only one of said articles to enter the slots thereof at a time; means for reciprocating said slide plate; and means for placing the articles in the slots of said slide plate.

3. Means for feeding a plurality of elongated articles into vertical aligned position in a receiving box comprising: a hopper terminating above said box; a plurality of vertically extending guide compartments in said hopper, the upper extremities of said compartments being elongated to receive said articles horizontally, the lower extremities thereof being reduced to discharge said articles vertically into said box; a horizontal top plate covering said hopper and provided with laterally extending elongated slots for receiving individual articles horizontally, each slot aligning with one of said compartments; a slide plate having similarly elongated slots positioned to register with the first slots when said slide plate is moved in one direction and to misalign therewith when moved in the other direction, said slide plate having a thickness sufficient only to allow only one of said articles to enter the slots thereof at a time; means for reciprocating said slide plate; a chamber plate above said slide plate having similarly elongated slots positioned to register with the slots in the slide plate when the latter are out of register with the slots in the top plate so that at each reciprocation each slot in the slide plate will simultaneously receive one article from said chamber plate and deposit it in a slot in said top plate.

4. Means for feeding a plurality of elongated articles into vertical aligned position in a receiving box comprising: a hopper terminating above said box; a plurality of vertically extending guide compartments in said hopper, the upper extremities of said compartments being elongated to receive said articles horizontally, the lower extremities thereof being reduced to discharge said articles vertically into said box; a horizontal top plate covering said hopper and provided with laterally extending elongated slots for receiving individual articles horizontally, each slot aligning with one of said compartments; a slide plate having similarly elongated slots positioned to register with the first slots when said slide plate is moved in one direction and to misalign therewith when moved in the other direction, said slide plate having a thickness sufficient only to allow only one of said articles to enter the slots thereof at a time; means for reciprocating said slide plate; a chamber plate above said slide plate having similarly elongated slots positioned to register with the slots in the slide plate when the latter are out of register with the slots in the top plate each of the slots in the chamber plate being of sufficient depth to contain a vertical pile of horizontal articles; and means for continuously

filling the slots in the chamber plate with articles.

5. Means for feeding a plurality of elongated articles into vertical aligned position in a receiving box comprising: a hopper terminating above said box; a plurality of vertically extending guide compartments in said hopper, the upper extremities of said compartments being elongated to receive said articles horizontally, the lower extremities thereof being reduced to discharge said articles vertically into said box; a horizontal top plate covering said hopper and provided with laterally extending elongated slots for receiving individual articles horizontally, each slot aligning with one of said compartments; a slide plate having similarly elongated slots positioned to register with the first slots when said slide plate is moved in one direction and to misalign therewith when moved in the other direction, said slide plate having a thickness sufficient only to allow only one of said articles to enter the slots thereof at a time; means for reciprocating said slide plate; a chamber plate above said slide plate having similarly elongated slots positioned to register with the slots in the slide plate when the latter are out of register with the slots in the top plate; and a slotted continuously traveling feed member moving in one direction over said chamber plate, the slots of the two being in alignment so that articles may drop from the slots of the feed member into the slots of the chamber plate to maintain the latter filled.

6. A cartridge box filling machine comprising: a multiple compartment hopper having a reduced lower extremity corresponding to the shape, arrangement, and position of the box to be filled; a horizontal top over said hopper provided with elongated cartridge receiving slots of sufficient length to receive a cartridge horizontally, there being one slot for each hopper compartment; a slide member moving over said top and having elongated slots corresponding to the receiving slots in said top each slot being shaped to receive a single horizontal cartridge; and means for horizontally placing cartridges in the slots of the slide member so that the movements of the latter will simultaneously deposit the cartridges in the receiving slots of the top when the slide member slots register with the top slots.

7. A cartridge box filling machine comprising: a multiple compartment hopper having a reduced lower extremity corresponding to the shape, arrangement, and position of the box to be filled, the compartments in said hopper being shaped to receive a cartridge in a horizontal position at the top and discharge it in a vertical position at the bottom; a horizontal top over said hopper provided with elongated cartridge receiving slots to receive a horizontally positioned cartridge, there being one slot for each hopper compartment; a slide member moving over said top and having elongated slots corresponding in shape and position to the receiving slots of said top; a chamber member above said slide member; elongated cartridge receiving chambers in said member registering with the slots in the slide member at one extremity of the latter's movement, each chamber being of sufficient depth to each receive a plurality of vertically stacked horizontal cartridges; and means for placing cartridges horizontally in said chambers.

8. A cartridge box filling machine comprising: a multiple compartment hopper having a

reduced lower extremity corresponding to the shape, arrangement, and position of the box to be filled; a top over said hopper provided with cartridge receiving slots, there being one slot for each hopper compartment; a slide member moving over said top and having slots corresponding to the receiving slots in said top; a chamber member above said slide member; cartridge receiving chambers in said member registering with the slots in the slide member at one extremity of the latter's movement; a traveling member moving horizontally over said chamber member; elongated cartridge receiving slots in said traveling member corresponding in size, shape, position and spacing to the chambers in the chamber member so as to receive and roll single cartridges across the slots in the chamber member so that they will fall therefrom into the chambers of the chamber member; and means for placing cartridges in the slots of the traveling member.

9. A cartridge box filling machine comprising: a multiple compartment hopper, the compartments being shaped to receive a horizontally positioned cartridge in their upper extremity and to discharge a vertically positioned cartridge from their lower extremity; means for supporting a cartridge box below said lower extremities; feeding means for simultaneously feeding cartridges into all of said compartments; a chamber plate for supplying cartridges to said feeding means, said chamber plate having a plurality of elongated slots of sufficient size to horizontally receive a cartridge and of sufficient depth to contain a plurality of cartridges in each slot; an endless belt; a pair of spaced-apart pulleys supporting said belt so that for a portion of its length it will slide over said chamber plate; a plurality of spaced-apart, laterally extending, elongated slots in said belt, each slot being of sufficient size to contain a single horizontal cartridge, said slots lying parallel to the slots in said chamber plate; means for placing cartridges in the slots of said belt so that they will be rolled over the slots in said chamber plate to maintain the latter filled as said belt travels; a feed hopper positioned adjacent said belt so that the latter will form one of the walls of the hopper and so that the slots therein will receive cartridges from said hopper by gravity; and means for maintaining the cartridges in the slots of said belt until they reach said chamber plate.

each slot being of sufficient size to contain a single horizontal cartridge, said slots lying parallel to the slots in said chamber plate; and means for placing cartridges in the slots of said belt so that they will be rolled over the slots in said chamber plate to maintain the latter filled as said belt travels.

10. A cartridge box filling machine comprising: a multiple compartment hopper, the compartments being shaped to receive a horizontally positioned cartridge in their upper extremity and to discharge a vertically positioned cartridge from their lower extremity; means for supporting a cartridge box below said lower extremities; feeding means for simultaneously feeding cartridges into all of said compartments; a chamber plate for supplying cartridges to said feeding means, said chamber plate having a plurality of elongated slots of sufficient size to horizontally receive a cartridge and of sufficient depth to contain a plurality of cartridges in each slot; an endless belt; a pair of spaced-apart pulleys supporting said belt so that for a portion of its length it will slide over said chamber plate; a plurality of spaced-apart, laterally extending, elongated slots in said belt, each slot being of sufficient size to contain a single horizontal cartridge, said slots lying parallel to the slots in said chamber plate; means for placing cartridges in the slots of said belt so that they will be rolled over the slots in said chamber plate to maintain the latter filled as said belt travels; a feed hopper positioned adjacent said belt so that the latter will form one of the walls of the hopper and so that the slots therein will receive cartridges from said hopper by gravity; and means for maintaining the cartridges in the slots of said belt until they reach said chamber plate.

CHARLES E. WALLICK.
